UNITED STATES PATENT OFFICE.

WILLIAM PERRY McCOMB, OF CONROE, TEXAS.

COMBINATION VALVE-CAP AND TOOL.

1,265,465.

Specification of Letters Patent.

Patented May 7, 1918.

Application filed November 13, 1916. Serial No. 131,113.

To all whom it may concern:

Be it known that I, WILLIAM PERRY McCOMB, a citizen of the United States, residing at Conroe, in the county of Montgomery and State of Texas, have invented certain new and useful Improvements in Combination Valve-Caps and Tools, of which the following is a specification.

The present invention has to do with improvements in devices designed particularly for deflating pneumatic tires, or removing valve members used in conjunction therewith. As is well known a valve for tires generally comprises a threaded stem in which is seated a valve core which includes a slender valve spring actuated rod and with this stem is provided a valve cap. My invention is designed as an attachment for these caps, it being understood, however, that the cap is provided with a stem which constitutes a core remover.

Caps of the general type of construction embodying core removing means are difficult to operate, or more strictly speaking, the removing operation is performed with much inconvenience due to the tendency of the cap to slip from the fingers when changing the grip during rotation of this member or cap. Again when it is desired to merely deflate a tire, one generally has to hunt for a slender article to insert into the valve stem for depressing the valve and such article must be held until the deflating operation is completed. It is to overcome these disadvantages that my invention has been designed as a complete article which may readily be used both to remove the core, being held in position on the stem during such operation, and for deflating purposes, when it is self sustaining, the article constituting in addition a cap for the valve stem.

To this end the invention consists in the construction, combination and arrangement of parts all as hereinafter more fully described, claimed and illustrated in the accompanying drawing, wherein:

Figure 1 is a side elevation of a pneumatic tire valve having my invention applied thereto.

Fig. 2 is a sectional view showing the use of my invention as a deflating device.

Fig. 3 is a similar view showing the use of the article as a core remover, the core being partially displaced.

Fig. 4 is a detail view of the device in the form of an attachment subject to disposition

upon a valve cap of conventional form for providing the combination article hereinbefore described.

Fig. 5 is a view of the gripping means shown in Fig. 4 before it is rolled into cylindrical form.

Throughout the following detail description, and on the several figures of the drawing, similar parts are referred to by like reference characters.

Referring to the drawing, and specifically describing the article, 1 designates a valve stem, and 2 the valve core seated therein, said core including the usual depressible valve rod 3. The numeral 5 designates a hollow body member which is internally threaded at one end so that it may be screwed upon the threaded extremity of the valve stem to constitute a cap therefor. This cap or body is formed with a stem 6 projecting centrally therefrom and this stem is notched at its extremity or more strictly speaking is grooved transversely as indicated at 6' so that it will straddle the upper end of the valve member 2 which, as customary, has opposing nibs 7 adapted to be received in the transverse groove just referred to. The stem extension, furthermore, is provided with a solid portion 8 directly adjacent to the notched extremity and in the use of the cap as a deflator this solid portion impinges against the valve rod 3 which is depressed when the extension 6 is moved into the entrance of the valve stem. The valve cap 5 has attached thereto in any desired manner gripping means which consists of a cylindrical shaped body 9, the material of which is preferably of resilient character. This body furthermore is formed with a series of yieldable fingers 10 that surround the cap stem 6 in spaced relation thereto. The gripping means just described may be soldered to the cap so as to hold it in fixed relation thereto, and the body of the gripping means is preferably split longitudinally as indicated at 11 so as to enable it to be positioned about the cap.

In Fig. 4 I have shown the gripping means as a unitary attachment which may be provided as an article of manufacture itself susceptible of being sold to the trade as such for attachment to valve caps of the general type described above.

It will be noted that the body portion of the form shown in Fig. 4 is split longitudinally and the material being resilient

the gripping means may readily be sprung open sufficient to permit of the attachment to the valve cap. Valve caps of this type are usually provided with a knurled portion centrally and coaction of this portion with the walls of the gripping means effectively holds the latter against movement when the article is used as a core remover. A groove 12 is preferably spun in the body of the gripping means which assists in positioning the member upon the valve cap.

Describing the use of the invention, when it is desired to deflate a tire the body of the device is unscrewed from the valve stem 1 and its position reversed, the stem 6 of the cap being introduced into the valve stem while the resilient fingers 10 engage upon the outer threaded portion thereof. The gripping action of these fingers is sufficient 20 to hold the cap on the valve stem with the cap stem pressing against the valve rod 3 during the deflating operation and the operator, of course may release his hold upon the cap by reason of this action. In a similar 25 manner when it is desired to remove the core or valve member from the stem the device is pushed on to the threaded extremity sufficiently far to enable the notched extremity of the stem 6 to straddle the nubs 7 30 on the valve. By rotating the device in the usual manner the valve will be unscrewed from its position and during such unscrewing the gripping fingers 10 effectively hold the device in place whenever it becomes necessary 35 for the operator to release the cap for the purpose of getting a renewed hold to continue the rotating operation.

It will be quite obvious that an article of this character possesses a distinct advantage by reason of the fact that one al-

ways has at hand a ready means for deflating the tire or removing a valve whenever he has a valve cap for the stem, provided with the means for holding it in operative positions shown in the drawing hereto attached. As an article of manufacture, furthermore, the gripping means may be easily and cheaply manufactured for ready attachment to the conventional valve cap of the general type involving the core removing means.

Having thus described my invention, what I claim as new is:

1. As a new article of manufacture, an attachment for valve stem caps comprising a sheet of resilient material rolled into an open-sided sleeve of substantially the same diameter as a cap and adapted to be sprung open for engagement around the cap for constituting holding means therefor during rotation of the cap when removing a valve, said sleeve being slit a plurality of times and the slotted portions bent inwardly to provide stem gripping fingers.

2. In a device of the class described, the combination with a valve stem cap, a sleeve surrounding the same and having a series of yieldable fingers arranged to extend upwardly from the cap for frictional engagement with a valve stem when removing a valve therefrom by means of the cap, the material of the sleeve at one end thereof being slightly flanged inwardly and also having a groove spun therein intermediate the length of the sleeve for holding the sleeve against relative displacement with respect to the cap.

In testimony whereof I affix my signature.

WILLIAM PERRY McCOMB.
